UNITED STATES PATENT OFFICE.

FRANK GUY LANG BIDDLECOMBE, OF LUTON, ENGLAND, ASSIGNOR TO THE WESTMINSTER CARBURETTOR COMPANY LIMITED, OF WESTMINSTER, ENGLAND.

APPARATUS FOR THE GENERATION OF COMBUSTIBLE GAS OR VAPOR FROM LIQUID FUEL.

1,147,363.

Specification of Letters Patent. Patented July 20, 1915.

Application filed December 13, 1912. Serial No. 736,521.

To all whom it may concern:

Be it known that I, FRANK GUY LANG BIDDLECOMBE, a subject of the King of Great Britain, and a resident of Luton, England, whose post-office address is 29 Kenilworth road, Luton, in the county of Bedford, England, have invented Improvements Relating to Apparatus for the Generation of Combustible Gas or Vapor from Liquid Fuel.

This invention relates to an apparatus for the generation of a combustible gas or vapor from heavy liquid hydrocarbon fuels such as paraffin that cannot be so readily vaporized as petrol or other of the lighter hydrocarbons.

The gas produced may be used for motive power purposes of many kinds and the apparatus—hereinafter called a generator—is modified according to the purpose for which the gas is to be used.

My device broadly speaking is as follows:—Fuel in a liquid state—either in the form of a stream or of coarse drops—is supplied to the generator simultaneously with a quantity of air sufficient to burn completely part of the fuel, the fuel is heated and vaporized, and a portion of the fuel is burnt by the aid of the air, all of which is used, while the remainder of the fuel, passing in an unburnt condition through this burning region, is thereby changed into a gas or vapor or mixture of both, which is employed for motive power purposes.

According to the present invention, the operation and control of my invention in its different stages, is accomplished by applying suction to one end of the generator, this serving to draw off the combustible gas produced, and to draw into the generator the fuel and the necessary supply of air, the fuel being drawn in through a nozzle and the air through a suitable part or parts.

The invention is especially applicable for use on motor vehicles, the suction then being provided by the induction stroke of the motor.

The apparatus as adapted for use on motor cars is comparable in action and efficiency with the jet carburetors for petrol.

In the accompanying drawings Figure 1 shows in vertical section a form of the invention, suitable for use on the internal combustion engines of motor cars. Fig. 2 is an

enlarged elevation of the air admission plug 55 and nozzle and Fig. 3 is a section on line 3^x of Fig. 2.

A cylindrical shell 1 is provided with a chamber 2 at the top having a fuel inlet passage 3 and the lower end of the shell is 60 closed by a shallow tray 4. This inlet 3 communicates with a connection-box 5 into which a tube 6 from a float chamber 7 projects, the float in the latter automatically controlling the supply from the main oil 65 tank, as in the well-known float-feed carburetor. A limited supply of air is also admitted into the box 5 through a perforated plug 8, described more fully hereafter. Within the shell 1 is an open hollow cylinder 9 situated so as to leave a space 10 between it and the shell 1. The lower end of the shell 1 is enlarged in diameter and then folded inwardly upon itself in the form of a thick flange 11 of special shape, 75 as hereinafter specified. The bottom 12 of the cylinder 9 does not touch the flange 11; its upper end is contracted at 13 and protrudes through the roof of the chamber 2, into a hollow top piece 14 fitted with a 80 flange 15 suitable for connecting directly or indirectly to the engine cylinder. The shallow tray 4 above mentioned is suspended by a rod 16 which extends upward throughout the combined length of the shell 1 and 85 piece 14, and, projecting through a gland or suitable opening in the latter, is provided externally with an eccentric 17, having a finger 18, by which the rod 16 may be raised or lowered. The effect of lowering 90 the latter is to lower the tray 4, until there is an air space between the edge of the tray and the open bottom or flange 11 of the shell 1. When raised again, the tray closes up against the flange 11. The lower end of 95 the rod 16 preferably carries a nut 19, above which is a spring 20, both of these being underneath the tray 4.

The external wall of the cylinder 9 is formed with an open spiral 21 serving 100 as a conduit for allowing the oil or mixture of oil and air to travel over a large area of the wall before reaching the bottom. The upper extremity of this spiral 21 is surrounded by a band 22 which prevents any air, vapor or spray from passing down below excepting along this portion of the spiral.

The receiving chamber 2 upon the top of the shell 1, communicates downwardly with fuel passages 23 situated immediately above the spiral 21.

5 The shape of the apparatus may be varied considerably without departing from its essential features.

The method of using the apparatus is as follows: The tray 4 is lowered, and supplied first with absorbent material such as an annular wick 24 and then with oil supplied from the nozzle 6 by holding open the valve-stem of the float-chamber 7, thus flooding the latter and causing an overflow of oil. 10 through the nozzle. When the wick is sufficiently soaked, it is ignited with a match. The engine is then started, and will begin to run with the gas given off by the burning material. The tray 4 is now raised, so closing the air space, and the supply from the oil tube 6 and air plug 8 enters the chamber 2 through the inlet 3 and passes down into the spiral 21 over the surface of the cylinder 9, which is now very highly heated owing 15 to the flame from the tray 4. The mixture catches fire before it reascends in the interior of the cylinder 9, but owing to insufficiency of air there is only partial combustion. The unconsumed fuel which passes to the engine is of a quality and calorific value sufficient to satisfy the requirements of a reliable gas producer for motive power purposes. The production of the combustible gas for use in the motor is then continuously carried on as follows:—Fuel (and air) 20 is sucked into the apparatus by the induction-stroke of the motor, and is then conveyed along the hot spiral 21 and vaporized to some extent; it then passes, together with a further supply of air, obtained through the holes 33 (subsequently described), into a zone where part of it is burnt, the air admitted being insufficient to burn it all, but enough to maintain a temperature in this 25 zone which will consume a small part of the succeeding charge of fuel and air, and heat the remainder sufficiently to complete the vaporization, or possibly produce a fixed gas. When starting the apparatus from cold, that part of the generator which vaporizes the fuel may be heated in the first instance by a torch or other suitable means, such as a wick fed with oil. The latter method, if part only of the oil in the wick 30 be burnt, serves to supply gas on which the motor can be run during the first few strokes. Any failure in the ignition can be restored while running (after a short stoppage) by means of a sparking plug 25, which 35 may be necessary when the throttle valve has been closed during a free run downhill.

The fuel is delivered to the generator in quantities proportional to the suction of the motor, and may be fed through a jet or 40 nozzle controlled by a float valve as in the

ordinary types of carburetors. Similarly the extra air supplied to the motor may be controlled by the suction of the same.

A particular combination of nozzle and threaded-air-plug has been devised by me as follows:—The central passage of the air plug 8 (shown by itself in Fig. 2) is closed at the bottom 26 and provided thereat with a very fine hole, and when the plug is screwed home the bottom 26 presses upon the top of the tube 6 which is really a plain pipe. Cross-passages 27 are provided for the oil and air to pass out into an annular cavity 28 (formed by reducing the thickness of this end of the plug) before being drawn into the inlet 3. If the fine hole through which the oil is admitted should become accidentally stopped, it can be easily reached by removing the plug 8, the hole being in the plug and not, as usual in the nozzle. 85

The flange 11 is channeled at 29 and formed with a baffle 30, the reason being that air is admitted to the channel 29 through holes 31, which are formed in an annular channel 32 having two or three entrances 33, which may be regulated, for the access of a limited supply of air. 90

In order to serve as a guide for the stem 16, the tray 4 has a central upturned core 34 through which the lower part of the stem 95 passes.

The combustible gas or vapor requires of course a further supply of air, before ignition in the combustion chamber of the motor can take place. This air may, if desired, be heated before admixture so that air and gas meet at approximately the same temperature. 100

It is not essential that any air at all be drawn in through the same passage as the paraffin for I do not require to obtain any vaporizing action such as might be imagined to take place similarly to the formation of petrol vapor when air is drawn past the paraffin nozzle. The two may therefore be drawn in quite independently through different passages. Where however they are drawn in through the same passage, they may be subsequently separated in an easy manner by interposing duplicate passages, a lower and a higher one. The paraffin will drop into the lower one, while the air will pass through the higher, and can be reintroduced to the paraffin vapor before they reach the fiery zone. 115 120

In forms of the invention other than those intended for use on motor cars, the suction may be produced by forced or natural draft or by any other suitable means and may be continuous or intermittent. 125

I claim:

1. A generator comprising a shell, a fuel feeding chamber above the shell and forming a part thereof, a cylinder supported within the shell, said cylinder having a spirally ar- 130

- ranged flange forming a fuel channel on its periphery, said chamber having an opening in its bottom for providing communication between the feeding chamber and the space between the cylinder and shell, said opening being arranged to direct fuel to the upper end of the channel, means supported at the base of the shell for heating the cylinder, and means for adjusting the first mentioned means with relation to the shell.
2. A generator comprising a shell, a cylinder in the shell, and arranged in spaced relation therewith, a spirally arranged flange on the cylinder, means supported above the cylinder for supplying fuel to the flange, means at the base of the cylinder for heating the cylinder, means for adjusting the means with relation to the cylinder and means for embracing the upper extremity of the flange for concentrating the flow of fuel to the flanges.
3. A generator comprising a shell, a fuel chamber above the shell and forming a part thereof, a cylinder supported within the shell, a spirally arranged flange on the cylinder, said flange forming a fuel channel to receive fuel from the fuel chamber, a tray supported under the shell, means in the tray for supplying heat to the cylinder, means extending into the shell for maintaining a fiery zone between the cylinder and the shell, and means for adjusting the tray with relation to the shell.
4. A generator comprising a shell, a fuel chamber above the shell, means for admitting fuel to the fuel chamber, a cylinder in the shell, a spirally arranged flange on the shell, said flange forming a fuel channel, said shell having air inlets adjacent the lower ends thereof, a baffle adjacent the openings, a tray adjacent the lower end of the shell, means in the tray for heating the cylinder and means for adjusting the tray with relation to the shell.
5. A generator comprising a shell, a fuel chamber above the shell, a cylinder in the shell, said cylinder having a spirally arranged flange said fuel chamber having openings for admitting fuel to the flange, a tray under the shell, means in the tray for adjusting the tray with relation to the shell.
